Primary Examiner — Susan Bennett Hattan*Assistant Examiner* — Rozita Mozaffarian(74) *Attorney, Agent, or Firm* — E J Asbury III, LLC(57) **CLAIM**

The ornamental design for electrical pliers with deburring feature, as shown and described.

DESCRIPTION

FIG. 1 is a front, left, and top perspective view of electrical pliers with deburring feature;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in FIGS. 1-7 illustrate features of the electrical pliers with deburring feature that form no part of the claimed design.

1 Claim, 5 Drawing Sheets(56)
